J. W. BURKE

MINE CAR COUPLER

Filed July 13, 1921

Inventor
J.W. Burke,

By *James Alberts*

Attorney

UNITED STATES PATENT OFFICE.

JAMES W. BURKE, OF ECCLES, WEST VIRGINIA.

MINE-CAR COUPLER.

Application filed July 13, 1921. Serial No. 484,386.

To all whom it may concern:

Be it known that JAMES W. BURKE, a citizen of the United States of America, residing at Eccles, in the county of Raleigh and 5 State of West Virginia, has invented new and useful Improvements in Mine-Car Couplers, of which the following is a specification.

The object of the invention is to provide a 10 simple and efficient form of coupler especially adapted for use in connection with mine cars and designed to provide for the effective automatic coupling of cars either on straight or curved portions of track without 15 necessitating manual operation of placement of the parts or the passing between the cars of attendants in either the coupling or uncoupling thereof, with a view to avoiding the accidents which are incident to such operations under the ordinary practice; and 20 with this object in view the invention consists in a construction and combination of parts of which a preferred embodiment is shown in the accompanying drawings.

25 wherein:—

Figure 1 is a longitudinal sectional view of a coupling embodying the invention.

Figure 2 is a plan view of the same.

Figure 3 is a horizontal section.

30 Figure 4 is a view of the uncoupling shaft.

The draw heads 10 and 11 are respectively mounted in guides or boxings 12 and 13, the draw head 10 preferably being provided with a stem 14 extending through a guide 15 and fitted with a cushioning spring 16 serving to relieve strain upon the draw heads in starting, said boxings being secured to the car bodies by means of suitable bolts 17, and the draw head 11 being pivotally mounted in 35 its boxing by means of a pin 18, with a sufficient looseness of engagement by reason of an enlarged opening 19, to permit of limited lost motion.

The draw head 10 is provided with a 40 spring cushioned slide 20 actuated by a coiled spring 21 and adapted to be held thereby in position to support the coupling pin 22 in an uncoupled position with its lower end above the throat 23, said coupling 45 pin being connected by a chain 24 or its equivalent with an arm 25 of an uncoupling shaft 26 mounted transversely on the car body and having a terminal operating arm 27 located at the side of the car.

50 Carried by the coupling head 11 for pivotal motion with relation thereto is a supple-

mental head 28, connected with a tongue 29 of the head 11 by means of a pivot pin 30, and the coupling link 31 which is carried by the supplemental head is adapted to extend 55 into the throat of the head 10 for repression of the slide 20 and engagement by the coupling pin 22, said link having a suitable opening 32 for the reception of the pin.

The supplemental coupling head and the draw head 10 are provided respectively with a spherically rounded seat 33 and a complementary spherically rounded head 34 for reception by the seat to permit of lateral relative swinging movement of the draw head 70 10 and supplemental coupling head 28 in turning curves and owing to the fact that the supplemental head is pivotally mounted by means of the pin 30 upon the draw head 11 it will be obvious that cars respectively 75 carrying said coupling members may be connected regardless of the sharpness of the curve upon which they may be positioned.

The coupling pin 22 when the coupling members are disengaged, being supported 80 by the slide 20, it is obvious that when the link 31 enters the throat of the draw bar 10 and engages the slide, the latter will be repressed to permit of the dropping of the coupling pin and hence the automatic interlocking 85 of the members of the coupler.

In order to normally secure the pivot pin 30 in position to secure the auxiliary coupler head to the draw bar 11, while permitting the removal thereof to disengage the auxiliary head when desired, a retaining arm 35 is shrunk on or otherwise secured to the pin 30 and is fitted with a depending lug 36 operating in a cavity 37 in the auxiliary coupler head, said lug having an ear 38 extending under an overhanging portion 39 of the coupler head when the retaining arm is in the position indicated in Figure 2. When it is desired to remove the pin 30, which can only be done when the members of the coupler are disengaged, the retaining arm may be swung to a central position in which the wing 39 is in registration, with a notch 40 communicating with the cavity 37. When the coupling members are engaged the retaining arm is held by the head 34 in the laterally displaced position indicated in Figure 2, to prevent displacement of the pin 30.

Having described the invention, what is claimed as new and useful is:—

1. A coupling comprising a pair of draw heads and an intermediate supplemental cou-

pling head, the latter having means for interlocking engagement with one of the draw heads, a pin pivotally connecting the supplemental coupling head with the other draw head, and means carried by the pivot pin and engageable with the first said draw head to lock the pivot pin in position.

2. A coupling comprising a pair of draw heads and an intermediate supplemental coupling head, the latter having means for interlocking engagement with one of the draw heads, a pin pivotally connecting the supplemental coupling head with the other draw head, and a retaining arm attached to the pivot pin and provided with means for interlocking engagement with the supplemental coupling head and being held in such interlocking engagement by the first said draw

head when it and said supplemental coupling head are interlocked.

3. In a coupling, a supplemental coupling head having a cavity provided with an overhanging shoulder, a pin pivotally mounted in said supplemental coupling head for pivotally attaching the latter to a draw head, and an arm fixed to the pin and having a lug received in the cavity, said lug having an ear adapted to engage under the shoulder, the supplemental head being adapted for interlocking engagement with a draw head so that the latter may move said ear under the shoulder.

In testimony whereof he affixes his signature.

JAMES W. BURKE.
